UNITED STATES PATENT OFFICE.

CHARLES T. BURLIN, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

FLIER.

1,230,272.

Specification of Letters Patent. Patented June 19, 1917.

Application filed August 9, 1913. Serial No. 783,850.

To all whom it may concern:

Be it known that I, CHARLES T. BURLIN, a citizen of the United States, residing at Whitinsville, in the county of Worcester and 5 State of Massachusetts, have invented the following-described Improvements in Fliers.

The improvements relate to fliers such as used on roving and twisting machines and involve certain novel features of structure 10 hereinafter described, which eliminate the special and difficult forging processes commonly necessary and thereby serve to reduce the cost of production. The new flier may be made in whole or in part of sheet metal 15 and is desirably formed in part of commercial sheet steel and in part of bar steel cut off and turned in an automatic lathe, the sheet steel and bar steel portions being permanently united by pressing, brazing, or 20 otherwise, so as to form a well-balanced and durable flier equal in all respects to the hand-forged article. The invention concerns the several parts independently and also in their 25 relation to the other parts, as will be apparent to those skilled in this art and as pointed out in the claims.

In the accompanying drawings I have illustrated the improved flier and the several parts and stages of its manufacture.

30 Figure 1 is a front elevation of the completed flier;

Fig. 2 is a side view thereof;

Fig. 3 a bottom plan view thereof;

35 Fig. 4 a flat sheet-metal blank from which the part which I term for convenience of reference, the supplemental section, is formed;

Fig. 5 the same blank when rolled up and ready to be bent;

40 Fig. 6 a sheet-metal blank from which the part I term the main sheet-metal section of the flier, is formed;

Fig. 7 the same blank after being rolled or bent into rounded or leg form;

45 Fig. 8 the supplemental section shown in Fig. 5 after bending;

Fig. 9 the main section of Fig. 7 after bending;

50 Fig. 10 shows the two sections in the act of assemblage;

Figs. 11 and 12 are respectively elevation

and top plan views of the neck section of the flier; and

Fig. 13 a plan of the flier ring.

Referring to the drawings, the flier proper 55 is composed of several parts or sections. The presser, marked 1, is of common form and function and constitutes no part of the present invention, except in so far as it cooperates with the presser mounting formed 60 on one of the legs of the flier and herein-after described. The main section is indicated generally by 3 and is composed of two leg portions of unequal length marked 3^a and 3^b, respectively, and an intermediate flat 65 portion 3^c. The supplementary section is indicated generally by 4 and is comprised of leg portions 4^a and 4^b, with an intervening flat portion 4^c. The neck section is indicated generally by 5, and the ring section 70 by 6. As shown in Figs. 6, 7 and 9, the main section 3 is formed from a flat blank stamped or cut from sheet metal in substantially the shape shown, which is determined with reference to the style of flier to be 75 made and the distribution of the weight therein. While in the flat form and if desired, coincidently with the cutting of the blank from the stock, two opposing shoulders or projections 7 are struck up from it 80 in such position as to serve as a presser mounting in the finished article. The end portions 3^a and 3^b of this blank are then each rolled or curled, as indicated in Fig. 7, the side margins of the portions 3^a being 85 brought nearly into butting contact with each other so as to form a narrow yarn slot, indicated by the curved line marked 8 in Figs. 2 and 7. The side margins of the blank 3^a are cut in curves which are complementary to each other so that the slot formed between them is also curved or staggered, as usual in fliers, for preventing escape of the yarn from the interior of the leg. The intermediate portion 3^c between the leg 90 portions is left flat or nearly so and punched with an aperture, the margin of which is drawn upwardly to form a boss 9, and such aperture and boss may be formed and desirably are formed while the section is in 100 the flat condition illustrated by Fig. 6, and may be done at the same time the blank is

cut from the stock. The rolled section is then bent over a suitable form into flier shape, as represented by Fig. 9, the upper rolled part of the leg portion 3^a forming the 5 familiar funnel-shaped entrance through which the yarn may pass into and through the leg.

The supplemental section 4 is formed of a flat blank of a contour such as shown in Fig. 10, which is also determined with reference to the style of flier and the desired distribution of the weight therein, and the leg portions 4^a and 4^b thereof are then rolled up, as indicated in Fig. 5. The intermediate 15 portion 4^c is left flat or substantially flat and punched with an aperture similar to that in the main section and also with a boss 10, which, however, projects downwardly from the aperture. This section is then bent 20 into flier shape, as shown by Fig. 8, and the two sections 3 and 4 are then brought together to be permanently united. This may be done in several ways, the preferred method consisting in telescoping one section 25 into the other, as, for example, by pushing the leg portion 3^b into the corresponding leg portion 4^b of the other section, and as shown by Fig. 10. When brought together in this manner, the leg 4^b which is left open at the 30 top to receive the other leg, can be folded down and the leg 4^a can be fitted snugly to the inner or under side of the leg 3^a, so that each section will thus reinforce the other, forming a stiff bridge of double thickness 35 between the parallel portions of the legs and on which to mount the neck, the bridge being further and materially reinforced by the bosses of the neck apertures. The sections are brazed or soldered as thus assembled, 40 forming practically a single piece. The apertures in the two sections will be brought into alinement by such assemblage and ready to receive the neck 5, which consists of a solid piece of metal centrally bored and 45 counter-bored so as to provide an interior seat for the spindle tip as well as a yarn entrance at the top and also a yarn outlet (12) at the side. A cross-pin 11 also is placed in the neck to lock with the spindle in the 50 usual way. The blank from which the neck is formed may be a cylindrical piece of steel, such as may be cut from round stock, and readily reduced in a lathe to the form shown in the drawings. The necessary operations thereon consist merely in the production 55 of a shoulder 13 and the internal and lateral borings, all of which can be accomplished with extreme rapidity and at slight expense on an automatic lathe. The small 60 end of the neck is inserted in the alined apertures of the sheet metal sections and pressed therein until the rim boss 9 engages substantially flush with the shoulder 13, whereupon it is soldered or brazed in such 65 position and firmly united to both sheet

metal sections. The two legs of the flier are then trued up and pressed into the desired finished shape, which may be done in any forming device. The ring section 6 is stamped of flat sheet metal and the hole 14 therein is pressed over the leg 4^b, and the other hole 15 over the opposite leg 3^a so as to space and brace the two leg portions of the flier, in such manner as to prevent distortion of, or possible injury to, the brazed 70 joint between the leg sections and the neck, notwithstanding that the flier be subjected to very rough usage. The ring also may be soldered or brazed to the legs, and if desired this may be done at the same time as the 75 brazing of the neck, the attachment being permanent in any event. The presser 1 is then mounted on the hollow leg 3^a with its upper ring 16 disposed between the struck up shoulders 7 above referred to, and its 80 lower ring 17 surrounding the lower end of the leg 3^a which is rounded at this point to form a journal and support for it. The flier as thus formed is then ready for finishing 85 and polishing but requires but little attention as to balancing, inasmuch as the proportions of metal on opposite sides of each sheet metal section have been predetermined to produce a balance as above mentioned.

From the description given, it will be 90 plain that it is immaterial to the general aspect of my invention whether the portion 3^b or 4^b is ultimately disposed upon the outside of the leg and that it is also immaterial of what length either of these leg portions 100 may be, provided they coöperate in producing a balanced and substantially symmetrical flier. It will be evident also that the length of the inner leg portion 3^b is immaterial to the specific flier illustrated except 105 in so far as it assists in providing counter-balance to the presser on the other leg, and that the principal function of the brace section 4 is to reinforce the flier at and around the neck 5, by providing double thickness at 110 that point, as above described. It will thus be plain that the substantive part of my invention may be present in a variety of different forms, such as may be comprehended by the terms of the following claims. 115

I claim:

1. A flier comprising a neck turned from cylindrical stock, and two legs formed of flat sheet metal rolled or folded into round leg-form, the material of said leg portions being overlapped to provide two thicknesses of the sheet metal at their junction with the neck. 120
2. A flier comprising a shouldered neck and two leg portions rolled up into round form from flat sheet metal, the sheet metal of said leg portions being overlapped to produce double thickness at the neck junction and apertured at that point to receive the neck, said double thickness portion being se- 125 130

cured to the said neck against the shoulder thereof.

3. A flier comprising a neck and two legs rolled up into rounded form from flat sheet metal which is apertured to receive the neck, the sheet metal of said leg portions being overlapped to produce double thickness at the neck junction, and a ring spacing the rolled legs near their lower ends.

10 4. A flier composed of two legs both rolled up out of a single strip of sheet metal, the junction between the legs being flattened and apertured, a supplementary apertured bridge section united to such flattened portion and a neck in both apertures.

5. A flier composed of a main section comprising two leg portions rolled up out of a single flat blank of sheet metal with an intervening flat portion between the rolled portions, a brace section having leg portions and adapted to reinforce the said flat portion, one of the leg portions of the said brace section being longer than the other leg portion thereof.

20 6. A flier composed of a main section comprising two leg portions rolled up out of a single flat blank of sheet metal with an intervening flat portion between the rolled portions, a brace section having leg portions and adapted to reinforce the said flat portion, one of the leg portions of the said brace section being longer than the other leg portion thereof and telescoped with the leg of the other section.

30 7. A flier composed of two leg portions which are rolled up out of a single strip of sheet metal and provided with a neck between its leg portion and a brace section having connected leg portions applied to the first mentioned leg portions on opposite sides of the said neck.

35 8. A flier composed of a main section formed of a sheet metal blank the end portions whereof are rolled into rounded or curved section and the intermediate portion whereof is substantially flat and provided

with a neck, and a supplemental bridge section also formed of sheet metal and applied to the other section on both sides of the neck, the two sections being permanently united. 50

9. A flier composed of two leg sections separately formed both out of flat metal and applied against each other to form a double thickness at the top, and a neck secured to both said sections. 55

10. A flier composed of two sections separately formed both of sheet metal and both provided with bossed apertures and permanently joined, forming a double thickness bridge, with such apertures in alinement 60 and a neck in such apertures permanently secured to both sections.

11. A flier composed of two sections assembled telescopically and one superimposed on the other at the top and a neck united to 65 both sections.

12. A flier, comprising two sheet metal sections applied one against the other at the bridge and having alined apertures with oppositely-projecting bosses, and a separate 70 neck in said bosses.

13. A flier comprising two sheet metal sections each rolled to form a leg, and the two sections overlapping at the bridge.

14. A flier comprising two sheet metal sections each having a rolled portion constituting a leg and a bridge portion, said bridge portions being overlapped and provided with registering apertures, and a neck 75 secured in said apertures. 80

15. A flier comprising two sheet metal sections having rolled leg portions assembled in telescopic relation, and bridge portions forming a double thickness at the neck.

In testimony whereof, I have signed this 85 specification in the presence of two witnesses.
